(57) **CLAIM**

I claim the ornamental design for a “payload enclosure,” as shown and described.

DESCRIPTION

FIG. 1 is a front perspective view of a payload enclosure having three sections and housing combinations of radio equipment, antenna(e), lighting system(s), or security system(s).

FIG. 2 is a rear perspective view of the payload enclosure shown in FIG. 1.

FIG. 3 is a top plan view of the payload enclosure shown in FIG. 1.

FIG. 4 is a front plan view of the payload enclosure shown in FIG. 1.

FIG. 5 is a side plan view of the payload enclosure shown in FIG. 1. The non-illustrated side of the payload enclosure is a mirror image of the illustrated side of the payload enclosure shown in FIG. 5; and,

FIG. 6 is a bottom plan view of the payload enclosure shown in FIG. 1.

The broken lines are only for illustrative purposes to show environmental structure and form no part of the claimed invention. Any surface shading is used solely to show the character or contour of the surfaces represented.
